(57) **CLAIM**

We claim the ornamental design for an oven range, as shown and described.

DESCRIPTION

FIG. 1 is a perspective view of an oven range showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view of an oven range, showing a second embodiment of our new design.

The broken lines in the drawing figures are included for the purpose of illustrating environment and form no part of the claimed design. Anything not shown in FIG. 8, the view showing the second embodiment, forms no part of the claimed design.
